United States Patent Office

Des. 193,773
Patented Oct. 9, 1962

193,773

TRAILER OR SIMILAR ARTICLE

James G. Johnston, Buena Park, Calif., assignor to Challenge-Cook Bros. Incorporated, Los Angeles, Calif., a corporation of California

Original application June 28, 1961, Ser. No. 65,742. Divided and this application Feb. 7, 1962, Ser. No. 69,063

Term of patent 14 years

(Cl. D14—3)

FIG. 3.

FIG. 4.

FIG. 5.

FIGURE 1 is a side elevational view, of a trailer or similar article showing my new design.

FIGURE 2 is a top view thereof.

FIGURE 3 is a perspective view thereof showing the side and rear.

FIGURE 4 is a front elevational view thereof.

FIGURE 5 is a rear elevational view thereof.

This is a divisional application of my co-pending application, Serial No. D. 65,742, filed June 28, 1961.

The tractor shown in broken lines in FIG. 1 is included for illustrative purposes only. The side not shown is a mirror image of the side shown in FIG. 1.

I claim:

The ornamental design for a trailer or similar article, substantially as shown and described.
